(57) **CLAIM**

The ornamental design for a garage screen door, as shown and described.

DESCRIPTION

FIG. 1 is a front elevational view of the garage screen door of the present invention, the rear view being a mirror image thereof;

FIG. 2 is a left side elevational view of the garage screen door of FIG. 1, the right view being a mirror image thereof; FIG. 3 is a top plan view of the garage screen door of FIG. 1;

FIG. 4 is a bottom plan view of the garage screen door of FIG. 1; and,

FIG. 5 is a front elevational view of an alternate embodiment of a garage screen door for a double door garage.
